[57] CLAIM

The ornamental design for a visual orientation device
for pedestrians, as described and shown.

DESCRIPTION

FIG. 1 is a perspective view of a visual orientation device
for pedestrians, showing my new design;

FIG. 2 is a front elevational view thereof;

FIG. 3 is a rear elevational view thereof;

FIG. 4 is a top plan view thereof.

The broken line disclosure is for illustrative purposes
only and forms no part of the claimed design.

Fig. 4.

—Ti—1.

Fig. 2.

Fig. 3.
